UNITED STATES PATENT OFFICE.

HARRY A. SEDGWICK, OF MILWAUKEE, WISCONSIN, ASSIGNOR TO THE CUTLER-HAMMER MFG. CO., OF MILWAUKEE, WISCONSIN, A CORPORATION OF WISCONSIN.

ALTERNATING-CURRENT MAGNET AND THE LIKE.

1,248,176.

Specification of Letters Patent. Patented Nov. 27, 1917.

Application filed February 20, 1915. Serial No. 9,630.

To all whom it may concern:

Be it known that I, HARRY A. SEDGWICK, a citizen of the United States, residing at Milwaukee, in the county of Milwaukee and 5 State of Wisconsin, have invented new and useful Improvements in Alternating-Current Magnets and the like, of which the following is a full, clear, concise, and exact description, reference being had to the accompanying drawing, forming a part of this 10 specification.

This invention relates to improvements in alternating current magnets, magnetic switches and other devices having attracted 15 parts which are pivotally mounted.

In practice, where a pivoted part is attracted by an alternating current magnet there is a tendency for such part to vibrate on its pivot and the degree of vibration is 20 materially increased by wear on the engaging pivotal parts. These conditions obtain even where shading coils or other means are provided to minimize vibration of the attracted part and the chattering of the attracted part on its pivot, is often very objectionable, especially after the pivotal parts have become worn.

This invention has among its objects to provide means to eliminate, or at least materially reduce, the vibration of the attracted 30 parts of alternating current devices at the pivotal points thereof.

A further object is to provide means for the aforesaid purpose which will compensate 35 for wear on the engaging pivotal parts.

Other objects and advantages will herein-after appear.

The accompanying drawing illustrates an alternating current switch provided with 40 one form of the invention and the same will now be described, it being understood that the invention is not limited to the specific form thereof selected for the purpose of illustration and is adapted for use in other 45 relations than that depicted.

The single view in the accompanying drawing is a side elevation of the switch.

The switch illustrated is of conventional form and of the double-pole type, the second 50 pole being identical with that appearing in the drawing. Briefly set forth the switch has two movable contact arms 1 operable by an alternating current magnet 2 to cooperate with stationary contacts 3. The magnet 2 is mounted in a suitable frame 4 fixed to

a panel 5 and has a pivoted armature 6 to which the two switch arms 1 are rigidly secured as by means of bolts 7. The armature member 6 has a hub 8 (dotted lines) revoluble on a shaft 9 supported in a clamping bearing 10 provided therefor on the magnet frame. Thus upon attraction of the armature to close the switch the hub 8 will turn on the shaft 9 and in consequence subject both of said parts to wear. In practice, 65 the hub 8 is preferably bifurcated or cut-away to straddle the clamping bearing 10 of the shaft 9.

The means illustrated to prevent vibration of the armature on its pivot consists 70 of a hooked member 11 having a single point bearing 12 on the forward side of the hub 8 and connected by a tension spring 13 to a fixed part 14. As illustrated, the part 14 comprises a right-angle plate secured by a bolt 15 primarily provided to secure the magnet frame to the supporting panel. The bearing end of the hooked member is preferably rounded and provided with a concave bearing surface on the hub 8 for freedom 80 of movement while said hooked member as a whole is so formed as to clear the hub except at the aforesaid bearing point. Further, the bearing point of the hook and the fixed end of the spring 13 are preferably so 85 disposed that the line of force will intersect or approximately intersect the axis of the armature 6. However, as will be obvious, pivotal movement of the armature member will shift the bearing of the hooked member 90 and this will slightly vary the relation of the line of force with respect to the axis of the armature. Where the hub is bifurcated to straddle the clamping bearing of the shaft 9 then the tension device just described is preferably duplicated for the two 95 sections of the hub.

It will thus be observed that the tension device exerts on the armature at all times a force directed substantially radially to 100 its axis. Moreover, it will be observed that this force is so directed as to complement the magnetic force exerted upon the armature at its point of fulcrum. Thus the tension device serves at all times to maintain 105 the pivotal parts of the armature in firm engagement and thereby tends to eliminate any chattering of the engaging pivotal parts. Moreover, the tension device is inherently adjustable to compensate for initial 110

loose fitting of the pivotal parts and for subsequent wear thereon, thereby insuring permanency of its effectiveness.

As employed in the switch illustrated the 5 primary purpose of the tension device is to maintain firm engagement of the pivotal parts and to this end said device is so designed as to divide equally any tendency which it may have to assist or oppose operation of the armature. In other words, the 10 arrangement is such that in operation of the switch the line of force exerted by the tension device is shifted across the axis of the armature and to equal degrees on opposite sides thereof. However, it will be readily apparent that the tension device may, if desired, be so arranged as to exert force in other relations with respect to the axis as, for example, to always bias the 15 switch to open position or to exclusively assist the magnet in closing the switch.

As above set forth, the invention may be embodied in various different forms and employed in other relations.

25 What I claim as new and desire to secure by Letters Patent is:

1. The combination with an alternating current magnet and armature therefor mounted upon a rigid pivot pin, of biasing 30 means engaging said armature to curtail chattering of its pivot parts, said means and said armature having an anti-friction bearing therebetween concentrating the biasing force of the former upon the latter.

35 2. The combination with an alternating current magnet and pivoted armature therefor, of a resilient device including a part having a pivotal bearing upon said armature, said device exerting a force upon said 40 armature through said pivotal bearing and in a direction substantially radially of the axis of said armature.

3. The combination with an alternating

current magnet and pivoted armature therefor, of a resilient device having a fixed part 45 and a pivotal connection with said armature, said device exerting a biasing force upon said armature, through said connection, substantially radially of the pivotal axis of said armature but variable with respect to said axis according to the positioning of said connection by said armature.

4. The combination with an alternating current magnet and pivoted armature therefor, of a resilient device having a fixed part 55 on one side of the pivotal axis of said armature and a pivotal connection with said armature on the opposite side of said axis, whereby said device exerts a biasing force upon said armature substantially radially 60 of its axis but variable with respect to said axis by movement of said connection by said armature.

5. The combination with an alternating current magnet provided with a supporting 65 frame, a rigid pivot rod carried by said frame and an armature mounted on said rod, of a spring having one end connected to a fixed part on one side of the pivotal axis of said armature and a hooked member 70 for connecting the other end of said spring to said armature on the opposite side of said axis, said spring exerting a biasing force upon said armature substantially radially of said pivot rod, and said hooked 75 member having a rounded end portion fitting into a concave bearing in said armature.

In witness whereof, I have hereunto subscribed by name in the presence of two witnesses.

HARRY A. SEDGWICK.
